US0D1085010S

(12) **United States Design Patent** (10) **Patent No.:** **US D1,085,010 S**
(45) **Date of Patent:** ** *Jul. 22, 2025

(54) **GENERATOR ASSEMBLY**

(71) Applicant: **NORTHERN TOOL & EQUIPMENT COMPANY, INC.**, Burnsville, MN (US)

(72) Inventors: **John Schuetz**, Owatonna, MN (US); **Kyle Hecimovich**, New Prague, MN (US); **Siddharth Mahajan**, Eagan, MN (US)

(73) Assignee: **NORTHERN TOOL & EQUIPMENT COMPANY, INC.**, Burnsville, MN (US)

(*) Notice: This patent is subject to a terminal disclaimer.

(**) Term: **15 Years**

(21) Appl. No.: **29/904,726**

(22) Filed: **Oct. 11, 2023**

(51) **LOC (15) Cl.** **13-01**

(57) **CLAIM**

The ornamental design for a generator assembly, as shown and described.

DESCRIPTION

FIG. 1 is a front, right perspective view of a generator assembly shown according to the present design;

FIG. 2 is a front, left perspective view thereof;

FIG. 3 is a left side elevational view thereof;

FIG. 4 is a right side elevational view thereof;

FIG. 5 is a rear end view thereof;

FIG. 6 is a front end view thereof;

FIG. 7 is a top plan view thereof; and,

FIG. 8 is a bottom plan view thereof.

The broken lines illustrate environment and portions of the generator assembly that form no part of the claimed design.

1 Claim, 8 Drawing Sheets
